COMBINED ELECTRICALLY OPERATED SWING FAUCET AND DISHWASHING FIXTURE

Herbert Carvel Moore, Los Angeles, Calif., assignor to
Electro-Way Corporation, Los Angeles, Calif., a corporation of California

Filed Jan. 22, 1962, Ser. No. 68,414

Term of patent 14 years

(Cl. D91—3)

FIGURE 1 is a perspective view of a combined electrically operated swing faucet and dishwashing fixture, showing my new design;

FIGURE 2 is a top plan view;

FIGURE 3 is an end elevational view; and

FIGURE 4 is another end elevational view.

The rear and bottom are substantially plain except for the brush, hose and hooks as indicated in FIGURES 1, 3 and 4.

I claim:

The ornamental design for a combined electrically operated swing faucet and dishwashing fixture, as shown and described.
